(57) **CLAIM**

The ornamental design for an electronic reader device, substantially as shown and described.

DESCRIPTION

FIG. 1 is a front perspective view of the electronic reader device in accordance with the present design;

FIG. 2 is a rear perspective view of the electronic reader device in accordance with the present design;

FIG. 3 is a front view of the electronic reader device shown in FIG. 1;

FIG. 4 is a rear view of the electronic reader device shown in FIG. 1;

FIG. 5 is a left side view of the electronic reader device shown in FIG. 1;

FIG. 6 is a right side view of the electronic reader device shown in FIG. 1;

FIG. 7 is a top view of the electronic reader device shown in FIG. 1; and,

FIG. 8 is a bottom view of the electronic reader device shown in FIG. 1.

Features illustrated in broken lines are shown for exemplary purposes only and form no part of the claimed design.
